UNITED STATES PATENT OFFICE.

TIMOTHY J. CARMODY, OF WATERBURY, CONNECTICUT, ASSIGNOR TO THE AMERICAN PIN COMPANY, OF SAME PLACE.

MACHINE FOR SEWING HOOKS AND EYES ON CARDS.

SPECIFICATION forming part of Letters Patent No. 650,553, dated May 29, 1900.

Application filed May 31, 1898. Serial No. 682,154. (No model.)

To all whom it may concern:

Be it known that I, TIMOTHY J. CARMODY, a citizen of the United States, and a resident of Waterbury, in the county of New Haven 5 and State of Connecticut, have invented certain new and useful Improvements in Machines for Carding Hooks and Eyes, of which the following is a full, clear, and exact description, whereby any one skilled in the art 10 can make and use the same.

My invention relates to that class of machines for sewing hooks and eyes upon cards, and more particularly to the means and devices for holding the card and thread during 15 the cutting operation, and also to the means by which the thread between the several cards is severed.

The object of my invention is to provide in a machine of this class means for holding and 20 severing the thread and for securing the thread; and to this end my invention consists in the device as a whole, in the combination of parts, and in the details and their combination, as hereinafter described, and more 25 particularly pointed out in the claims.

Referring to the drawings, Figure 1 is a top or plan view of the table and parts mounted thereon, illustrating my invention, the sewing mechanism being removed. Fig. 2 is a view 30 in front elevation of the same, showing the needle and needle-bar in relation thereto. Fig. 3 is a view in side elevation, looking from the left of the machine as shown in Fig. 1, the sewing mechanism being removed. Fig. 35 4 is a detail perspective view of the cutter-box. Fig. 5 is a diagram view illustrating the mechanism with the cutter in its normal position. Fig. 6 is a detail diagram view illustrating the position of the parts with the cutter in position to sever a thread.

In order to enable hooks and eyes to be attached to cards, as by means of a sewing-machine, a holder has been provided supporting connected hooks and eyes in proper position 45 with relation to each other and also in a position having particular reference to the card on which they are to be sewed, the whole being fed along the sewing-machine and across the path of movement of the needles by means 50 of ordinary known devices for such purposes. The hooks and eyes are sewed to a card in

limited numbers—that is, in two or more rows, making up a dozen or other desired number of the hooks and eyes on each card. This operation requires a separation of the card 55 or contemplates the use of separate cards, and as the thread used in the sewing-machine is of a continuous length it must be cut between the cards.

In prior devices of the class illustrated and 60 described herein an objection has been found from the fact that at that edge of the card near which the last stitch is taken the thread is left more or less loose in the needle-hole, and if any pull is exerted on the loose end 65 there is danger of unraveling the whole length of stitches, thus severing the hooks and eyes from the card. It is therefore desirable to fasten this last stitch in some way, and by 70 my improvement such means are provided. A further objection to prior devices of this class has resided in the fact that in severing the thread after the last stitch has been made 75 the application of the cutter to the stitch pulls upon the thread to an extent to cause the unraveling hereinbefore referred to, and I have provided means herein for holding the thread in such manner during the cutting operation that this unraveling is prevented. My invention also provides means for holding the ends 80 of two cards so that they will not be carried upward by the cutter in the cutting operation. I have also provided means whereby the cutter will operate quickly, so as not to interfere with the forward movement of the cards 85 on which the hooks and eyes are being sewed.

In the accompanying drawings the letter *a* denotes the table of an ordinary sewing-machine, the mechanism for feeding the thread and for operating the needles being of any 90 usual and well-known type.

On the table *a* are secured supports *b*, in which are mounted feed-shafts *b'*, supporting feed-pinions *b²* and driving-pinions *b³*. The driving-pinions are operatively connected by 95 means of gears *b⁴*, located between the pinions, one of the gears being operatively connected with a feed-ratchet *c*, operated by a pawl *c'*, pivoted to an arm *a²*, secured to the ordinary feed-shaft *a'* of the machine.

In the operation of the device a holder *d* is provided with hooks and eyes *d' d²*, held

thereon with the eye portions projecting beyond the edge and in-position to receive the needles a^3 . This holder is provided on its upper surface with a rack adapted to engage the feed-pinions b^2 and on its under surface with a lug d^3 , adapted to lie against the edge of the card and push it forward as the holder is fed through the device in the rotation of the feed-pinions, the needles passing through the loops of the hooks and eyes and fastening them to the card.

A duplicate set of feed-pinions is illustrated herein and the hooks and eyes are held on the holder by means of spring-fingers, which allow the card, with the hooks and eyes secured thereto, to be removed from the holder by the application of slight force.

The mechanism above described is of old and well-known construction and forms, except in combination with the parts to be hereinafter described, no part of the present invention.

On the stud c^3 , carrying the feed-ratchet c , is loosely mounted a cutting-ratchet c^3 , held against backward movement, as by means of a detent c^4 . The ratchets c and c^3 project through the table a to an extent to be engaged by pawls c^5 and rotated thereby in the reciprocating movement of the feed-shaft a' . The cutter-ratchet c^3 is rotated in an opposite direction from the ratchet c , a cam projection c^6 in the rotation of the ratchet engaging a shoulder e' on the main rock-shaft e . A plunger-arm e^2 extends from the rock-shaft e , to which is pivoted a rod e^4 , the opposite end of the rod being pivoted to an arm f' , secured to a plunger rock-shaft f . This rock-shaft is suitably mounted in a standard supported on the table, the opposite end of this rock-shaft supporting an arm f^2 , to the lower end of which is pivoted a plunger-wheel f^3 . This arm f^2 is preferably made in two sections, adjustably connected.

A plunger-guide g is supported on the table, through which extend pluggers h' and guide-rods h^2 , these pluggers and guide-rods being secured to the plunger-support h . A shoulder h^3 is formed on the plunger-support, against which the plunger-wheel f^3 strikes in the swinging movement of the arm f^2 . A spring h^4 causes one of the arms on the wheel to lie in normal position to surely engage the shoulder h^3 . The pluggers h' are made of a length to lie in close proximity to the table a when the plunger-support is at the lower limit of its play and for the purpose of clamping a card between the pluggers and the table, the pluggers being suitably spaced to overlie a needle-hole made in the operation of sewing the hooks and eyes to the card.

A cutter-arm i is secured to the main rock-shaft e , the opposite end of the cutter-arm having secured thereto a cutter k , that projects across underneath the table in a position to underlie the cards on which the hooks and eyes are being secured, a spring k' holding the cutter normally at the rearward limit of

its play and against a cutter-stop k^2 , adjustably mounted in the cutter-stop support k^3 .

The forward end of the cutter projects into a cutter-box l , and a cutter-cam m is pivoted to the cutter in a position to lie in the cutter-box. A cam-shoulder is formed in the slot l^2 in the cutter-box, this shoulder being preferably formed of a separate piece lying within the slot and adjustably secured to the box. A spring l^4 is employed for holding the cutter normally at the lower limit of its play. The cutter-box l is adjustably mounted in a bracket l^3 , secured to the table. The means for moving the box on the bracket and for adjustably securing the box to the bracket and holding it adjustably thereon may be of any form desired. In the form herein shown the box l has a projection of dovetail shape fitting a groove of the same shape in the bracket l^3 , (see Fig. 4,) and a set-screw (not shown) may be employed for holding the box in position.

The operation of the device is as follows: The hooks and eyes having been placed in position on the holders and a card inserted underneath the holder, the rack of the holder is engaged with a feed-pinion b^2 to an extent to allow the card to underlie the needles. The machine being started, the reciprocation of the feed-shaft a' causes the pawl c' to rotate the ratchet-feed c in a step-by-step movement, which operation feeds the card underneath the needle. This operation of the rock-shaft also causes the cutter-ratchet to be rotated in a step-by-step movement by means of the cutting-pawl c^5 . This step-by-step movement is so timed that the projection c^6 will engage the shoulder e' on the main rock-shaft at about the time the needles are sewing the last hook and eye to the card, and in any event at such time as to cause the main shaft to be rocked to cause the thread to be severed just after the last hook and eye has been secured to the card. The movement of the main rock-shaft e causes the operation of the plunger rock-shaft, swinging the arm f^2 and causing the plunger-wheel to engage the shoulder h^3 on the plunger-support, forcing the latter downward and causing the pluggers h' to press the card against the table, each of the pluggers coming in contact with a hole formed by a needle and forcing the material into the hole and closing the same to prevent the thread from pulling out. In this operation the plunger-support is forced gradually downward, the pluggers being held in contact with the card, however, but for an instant, and as one of the arms on the wheel passes the center the force of the springs on the pluggers carries the plunger-support quickly upward, which movement is permitted by the free rotation of the wheel on its pivot. The movement of the main rock-shaft e also swings the cutter-arm i , causing the cutter k to be moved forward, in which operation the cutter-cam m , coming in contact with the cam-shoulder l^2 in the cutter-

box, forces the cutter upward against the tension of the spring k^4 . This cutter-cam is so formed that the cutter makes engagement with the card to an extent to sever the thread, the several parts being so timed that the pluggers press the card to the table just before the cutter operates to sever the thread, this pressing of the pluggers on the card holding the thread tightly and preventing its pulling through the holes under the pressure of the cutter. As a point on the cutter-cam passes a central line through said point and the pivot the cutter is drawn quickly downward under the force of the spring k^4 . This quick movement of the cutter and of the pluggers away from the cards is for the purpose of allowing the free forward movement of the cards from the machine under its continued operation. The cutter is drawn quickly backward under the force of the spring k' until it rests with the arm i in contact with the stop k^2 . The next card is fed into the machine until the required number of hooks and eyes are secured thereto, when the operation of the plunger and cutter is repeated.

I claim as my invention—

1. In combination in a machine for sewing hooks and eyes to cards including a support, a holder for hooks and eyes, mechanism for moving the holder on the support, means for sewing the hooks and eyes to the cards, a cutter-blade having its cutting edge formed lengthwise along one edge of the blade, means for holding the material in opposition to the cutter, and means for moving the cutter simultaneously in a longitudinal and in a transverse direction thereof against the material to be severed.
2. In combination in a machine for sewing hooks and eyes to cards including a support, a holder, mechanism for moving the holder on the support and means for sewing the hooks and eyes to the cards, a cutter-blade, and means for moving the cutter in a transverse direction in a curved line against the material to be severed.
3. In combination in a machine for sewing hooks and eyes to cards including a support, a holder for hooks and eyes, mechanism for moving the holder on the support, and means for sewing the hooks and eyes on the card, a cutter-blade, means for holding the material to be severed in opposition to the cutter, and means for moving the cutter in a transverse direction in a curved line against the material to be severed.
4. In combination in a machine for sewing hooks and eyes to cards including a support, a holder for hooks and eyes, means for moving the holder along the support, and means for sewing the hooks and eyes to the cards, a cutter, and means for moving the cutter against the material to be severed and away from it in the forward movement of the cutter.
5. In combination in a machine for sewing hooks and eyes to cards including a support,

a holder, means for moving the holder on the support, and means for sewing hooks and eyes to the cards, a cutter and means for moving the cutter in a curved line against and away from the material to be severed in the forward movement of the cutter.

6. In combination in a machine for sewing hooks and eyes to cards including a support, a holder for hooks and eyes, means for moving the holder along the support and means for sewing hooks and eyes to the cards, a cutter, means for holding the material to be cut in opposition to the cutter, and means for moving the cutter toward and away from the material to be cut in the forward movement of the cutter.

7. In combination in a machine for sewing hooks and eyes to cards including a support, a holder for hooks and eyes, means for moving the holder along the support and means for sewing the hooks and eyes to the cards, a cutter, a cam pivoted to the cutter and having a support, and means for moving the cutter endwise.

8. In combination in a machine for sewing hooks and eyes to cards including a support, a holder for hooks and eyes, mechanism for moving the holder along the support and mechanism for sewing hooks and eyes to the cards, a cutter, a cam pivoted to the cutter, a stop to prevent sliding movement of the cam, and means for moving the cutter endwise.

9. In combination in a machine for sewing hooks and eyes to cards including a support, a holder for hooks and eyes, means for moving the holder along the support and means for sewing hooks and eyes to the cards, a cutter, an angularly-shaped cam pivoted to the cutter, a stop to prevent sliding movement of the cam, and means for moving the cutter endwise.

10. In combination in a machine for sewing hooks and eyes to cards including a support, means for moving the holder on the support and means for sewing hooks and eyes to the cards, pluggers adapted to overlie the holes made by the needles in sewing, and means for pressing the pluggers against the card at the points where pierced by the needles.

11. In combination in a machine for sewing hooks and eyes to cards including a support, a holder for hooks and eyes, means for moving the holder along the support and means for sewing hooks and eyes to the cards, a cutter, means for moving the cutter against the material to be severed, pluggers overlying the card at one side of the line of contact with the cutter, and means for pressing the pluggers against the material to be severed during the cutting operation.

12. In combination in a machine for sewing hooks and eyes to cards including a support, a holder for hooks and eyes, means for moving the holder along the support and means for sewing hooks and eyes to the cards, a cutter-box underlying the support, a cutter with one end projecting into the box, a cam piv-

oted to the cutter, a stop adapted to engage the cam, means for moving the cutter lengthwise, and means for withdrawing the cutter.

13. In combination in a machine for sewing hooks and eyes to cards including a support, a holder for hooks and eyes, means for moving the holder along the support and means for sewing hooks and eyes to the cards, pluggers adapted to overlie the holes made by the needles in sewing, means for pressing the pluggers against the card at such points, and means for withdrawing the pluggers.

14. In combination in a machine for sewing hooks and eyes to cards including a support, a holder for hooks and eyes, means for moving the holder along the support and means for sewing the hooks and eyes to cards, a cutter, a bracket, a cutter-box adjustably secured to the bracket, and means for moving the cutter within the box.

15. In combination in a machine for sewing hooks and eyes to cards including a support, a holder for hooks and eyes, means for moving the holder on the support and means for sewing hooks and eyes to the cards, a ratchet, means for rotating the ratchet, pluggers overlying the card, and operative connections between the pluggers and ratchet.

16. In combination in a machine for sewing hooks and eyes to cards including a support, a holder for hooks and eyes, means for moving the holder along the support and means for sewing hooks and eyes to the cards, a ratchet, a rock-shaft operatively connected with the ratchet, a cutter connected with the rock-shaft and pluggers also operatively connected with said rock-shaft.

17. In combination in a machine for sewing hooks and eyes to cards including a support, a holder for hooks and eyes, means for moving the holder along the support and means for sewing hooks and eyes to the cards, plug-

gers overlying the support, a plugger-support with pluggers secured thereto, a plugger rock-shaft, a wheel supported by the rock-shaft and adapted to engage the plugger-support, and means for operating the rock-shaft.

18. In combination in a machine for sewing hooks and eyes to cards including a support, a holder for hooks and eyes, means for moving the holder along the support and means for sewing hooks and eyes to the cards, a plugger rock-shaft, a plugger-support with pluggers secured thereto, a wheel pivoted to the rock-shaft and adapted to engage said support, and means for operating the rock-shaft.

19. In combination in a machine for sewing hooks and eyes to cards including a support, a holder for hooks and eyes, means for moving the holder along the support and means for sewing hooks and eyes to the cards, a plugger rock-shaft, a plugger-support secured thereto, a shoulder on the support, a wheel pivotally supported by said rock-shaft and adapted to engage a shoulder on the support, and means for operating said rock-shaft.

20. In combination in a machine for sewing hooks and eyes to cards including a support, a holder for hooks and eyes, means for moving the holder along the support and means for sewing hooks and eyes to the cards, a main rock-shaft, a cutter having one end supported by said rock-shaft, means for moving the cutter against the material to be severed, a plugger rock-shaft operatively connected with the main rock-shaft, a plugger-support with pluggers thereon, a wheel supported by the plugger rock-shaft and adapted to operate the plugger-support, and means for operating the main rock-shaft.
